CLAIM

The ornamental design for an electronic cigarette atomizer as shown and described.

DESCRIPTION

- 1.1: Perspective
- 1.2: Perspective
- 1.3: Front
- 1.4: Back
- 1.5: Left
- 1.6: Right
- 1.7: Top
- 1.8: Bottom

Reproductions 1.1 and 1.2 are respectively top and bottom perspective views of the electronic cigarette atomizer con-

(Continued)

stituting the present design; reproductions 1.3 to 1.8 are respectively front, rear, left side, right side, top and bottom views thereof.

The broken lines in the drawings depict portions of the electronic cigarette atomizer that form no part of the claimed design.

1 Claim, 8 Drawing Sheets
